METHOD OF PREPARING WASHING COMPOSITION

Vladimir Dvorkovitz, Kansas City, Mo., and Jerome Arthur Goldman, Evanston, Ill., assignors to The Diversey Corporation, Chicago, Ill., a corporation of Illinois

No Drawing. Filed Aug. 13, 1957, Ser. No. 677,853

8 Claims. (Cl. 252—138)

This invention relates to a process of producing a particulate detergent composition having a nucleus of inorganic material and a coating of a relatively neutral, reaction-set salt of a synthetic organic, acidic wetting agent, which comprises spraying solid particulate inorganic alkaline material with a normally slow-reacting member of the class consisting of higher alkyl aryl sulfonic acids, higher alkyl sulfonic acids, higher alkyl sulfuric acid esters, and admixtures thereof in the presence of a small amount of reaction promoting liquid, whereby said member is completely reacted with said alkaline material and a dry, solid, coated, finely divided detergent composition is produced at once during the neutralization reaction.

The term "normally slow-reacting" herein refers to the fact that when the particulate alkaline material is sprayed with the acidic wetting agent, in the above process, in the absence of the reaction promoting liquid, the wetting agent slowly reacts with the alkaline material.

This application is a continuation-in-part of our pending application Serial No. 427,677, filed May 4, 1954, now abandoned, which, in turn, was a continuation-in-part of our copending application Serial No. 348,572, filed April 13, 1953, now abandoned.

Although synthetic organic, acidic wetting agents from the class consisting of higher alkyl aryl sulfonic acids, higher alkyl sulfonic acids, higher alkyl sulfonic acid esters, and admixtures thereof have some detergent properties as such, their detergent properties are materially improved by neutralizing them with inorganic alkaline material.

In the past, this neutralization reaction has been conducted in aqueous solution since the presence of comparatively large quantities of water has been heretofore necessary to induce a neutralization reaction between these slow-reacting acidic wetting agents and inorganic alkaline material. In order to produce a dry composition after such a homogeneous reaction, the neutralized reaction products must be dried (e.g., in drum dryers) in order to volatilize the water. After such products are dried, they must be ground in order to produce a finely divided, free flowing detergent product.

We have discovered a process by which the normally slow-reacting synthetic organic, acidic wetting agent rapidly and completely reacts with the inorganic alkaline material to form a particulate composition without requiring either a separate drying step or grinding the reaction product. This heterogeneous process for producing a particulate detergent composition having a nucleus of inorganic material and a coating of a relatively neutral, reaction-set salt of a synthetic organic, acidic wetting agent, comprises: spraying solid particulate inorganic alkaline material with a normally slow-react-

2

ing member of the class consisting of higher alkyl aryl sulfonic acids, higher alkyl sulfuric acid esters, higher alkyl sulfonic acids, and admixtures thereof in the presence of a small amount of reaction promoting liquid (e.g., glycol, alcohol, sulfuric acid), whereby said member is completely reacted with the alkaline material and a dry, solid, coated, finely divided detergent composition is produced at once during the neutralization reaction. By spraying an excess of inorganic alkaline material with the synthetic organic, acidic wetting agent, some of the inorganic alkaline material will remain unreacted after all the organic wetting agent has been neutralized. The excess unreacted alkaline material serves as an inorganic detergent builder. This process may be carried out in a closed, horizontally extending reaction vessel having horizontally rotating mixing paddles therein and a stationary, horizontally extending, overhead pipe with spray nozzles which spray the liquid material on to the alkaline material. It is preferable to premix the reaction promoting liquid with the acidic wetting agent, although each of these constituents may be separately applied to the particulate alkaline material.

The reaction promoting liquid thus serves to enable the acidic wetting agent to promptly and completely react with the inorganic alkaline material to form solid, free-flowing particles having improved detergency and obviates the need for a drying step. In the event the inorganic alkaline material is sprayed with the organic acid material in the absence of the reaction-promoting liquid, a free-flowing product will not be produced, instead a discolored (i.e., brown) gummy mass will result; in addition, the reaction between the inorganic alkaline detergent and acid wetting agent will continue over an extended period of time which may encompass several days or more, whereas complete neutralization may be effected in our process in about 3-5 minutes.

Our process produces a washing composition that is in the form of finely divided particles, each of which comprises a nucleus of inorganic alkaline material surrounded by the neutralized reaction product (i.e., salt) produced by the interaction of the acidic wetting agent with a portion of the alkaline material. Thus, the pH of the particles as a whole is markedly in excess of the pH of the neutralized surface areas thereof. This enables the particles to be added to water to form a solution having a pH below about 8 during the period that the particles are being hand agitated in the water and are in direct contact with the skin. Under such conditions, subsequent roughening and chapping of the hands are lessened.

The term "reaction promoting liquid" includes glycols, alcohols, sulfuric acid and admixtures thereof, which may be sprayed with the synthetic organic, acidic wetting agent on to the particulate alkaline material. For example, liquids may be used, such as ethyl alcohol, methyl alcohol, isopropyl alcohol, butyl alcohol, ethylene glycol, diethylene glycol, propylene glycol, and other similar water-soluble organic compounds, which increase the reaction rate of the wetting agent with the particulate alkaline material. We prefer to employ diethylene or propylene glycol rather than volatile materials in order to minimize fire hazards. Although minor amounts of water as well as admixtures of water with glycol and/or alcohol and/or sulfuric acid serve to promote the reaction between the synthetic organic acidic wetting agent and the alkaline material, the use of water requires very careful controls, since excessive levels thereof, cause the

formation of a gummy undivided mass; on the other hand, alcohols, glycols, and sulfuric acid do not require such careful control of the levels used. Thus, water is clearly distinguishable from the glycols, alcohols, sulfuric acid, or aqueous dilutions thereof, and its use is restricted to conditions which permit very careful control of the level present in the mix of alkaline material and synthetic organic, acidic wetting agent.

The synthetic organic wetting agent is restricted to a member of the class consisting of higher alkyl aryl sulfonic acids, higher alkyl sulfonic acids, higher alkyl sulfuric acid esters, and admixtures thereof. For example, such wetting agents include dodecyl benzene sulfonic acid, mahogany acids, octadecyl sulfuric acid ester, lauryl sulfuric acid ester, dodecyl sulfonic acid, and the like.

The inorganic alkaline material serves to neutralize the synthetic organic, acidic wetting agent and the excess unreacted portion, which constitutes the nucleus of our particulate detergent composition, serves as a detergent builder. This alkaline material may include such inorganic alkalies as caustic, sodium carbonate, sodium tripolyphosphate, sodium silicates, sodium bicarbonate, any of the other alkalies employed in the detergent field, and admixtures thereof.

The following samples are typical particulate detergent compositions of this invention which employ a sulfonic acid as the synthetic organic, acidic wetting agent. An admixture of the wetting agent and reaction promoting liquid were sprayed on the particulate inorganic material.

Formulations containing substantially the same ingredients and portions as those of Samples 1, 3, 5, 7, 9, 11, 13, and 20-26 were prepared except that in each case ethyl alcohol was employed in place of the diethylene glycol reaction promoting liquid. The resulting coating about the nucleus of particulate alkaline material did not retain the reaction promoting liquid since the ethyl alcohol was evaporated by the heat of reaction.

Formulations were prepared which contained the same ingredients and proportions of Samples 20-26, however, 50 lauryl sulfuric acid ester was substituted for octadecyl sulfuric acid ester.

Formulations were also prepared which contained substantially the same ingredients and proportions as those of Samples 20-26, with the exception that the levels of 55 wetting agent were decreased 53% of the indicated values and the levels of sulfuric acid were increased 300% of the indicated values.

Formulations were also prepared which contained substantially the same ingredients as Samples 1, 13, 20 and 60 26, except that the indicated levels of wetting agent contained a mixture of equal parts by weight sulfonic acid and sulfuric acid ester.

Substantially similar levels of higher alkyl sulfonic acids such as dodecyl sulfonic acid may be substituted 65 for the wetting agent set forth in the above samples.

The levels of reaction promoting liquid used in our process should be at least about $\frac{1}{8}$ to $\frac{1}{4}$ the weight of

the acidic wetting agent. The level of synthetic organic, acidic wetting agent may be at low as 0.5% by weight of the reaction mixture and as high as about 45-50% by weight of said mixture.

5 The foregoing detailed description has been given for clearness of understanding only, and no unnecessary limitations should be understood therefrom, as modifications will be obvious to those skilled in the art.

We claim:

10 1. The process of producing a particulate detergent composition consisting essentially of a nucleus of inorganic material and a coating of a relatively neutral, reaction-set salt of a synthetic organic, acidic wetting agent, which comprises: spraying solid particulate inorganic alkaline material which serves as a detergent builder with about 0.5-50% by weight, based on the weight of the reaction mixture, of a substantially anhydrous normally slow-reacting member of the class consisting of higher alkyl aryl sulfonic acids, higher alkyl sulfonic acids, higher alkyl sulfuric acid esters, the alkyl groups in said sulfonic acids and said sulfuric acid esters containing about 12-18 carbon atoms and admixtures thereof in the presence of at least about 20% by weight, based on the weight of said reacting members, of a substantially anhydrous reaction promoting liquid consisting essentially of a member of the group consisting of lower alkylene glycols having about 2-4 carbon atoms, lower alkyl alcohols having about 1-4 carbon atoms, concentrated sulfuric acid, and admixtures thereof, whereby said member is completely reacted with said alkaline material during a period of up to about 5 minutes and a dry, solid, coated, finely divided detergent composition is produced at once during the neutralization reaction.

2. The process of claim 1 wherein the reaction promoting liquid is concentrated sulfuric acid.

3. The process of claim 1 wherein the reaction promoting liquid is a lower alkylene glycol having about 2-4 carbon atoms.

4. The process of claim 1 wherein the reaction promoting liquid is diethylene glycol.

5. The process of claim 1 wherein the reaction promoting liquid is propylene glycol.

6. The process of claim 1 wherein the reaction promoting liquid is a lower alkyl alcohol having about 1-4 carbon atoms.

7. The process of claim 1 wherein said inorganic alkaline material consists essentially of at least one member of the group consisting of caustic soda, soda ash, sodium silicates, sodium bicarbonate, and sodium phosphates.

8. The process of claim 1 wherein said inorganic alkaline material contains soda ash.
